UNITED STATES PATENT OFFICE.

CALVIN T. CUNNIUS, OF LONG BRANCH, NEW JERSEY.

COLUMN.

No. 902,209.

Specification of Letters Patent. Patented Oct. 27, 1908.

Application filed April 8, 1908. Serial No. 425,956.

To all whom it may concern:

Be it known that I, CALVIN T. CUNNIUS, a citizen of the United States, and a resident of Long Branch, in the county of Monmouth and State of New Jersey, have invented a new and Improved Column, of which the following is a full, clear, and exact description.

This invention is an improvement in columns, relating primarily to columns built up of a plurality of staves, usually of wood and joined together by a suitable number of hoops or bands.

Stave columns, especially for outside work, as now generally constructed are not lasting, for the reason that the joints between the staves soon break and the staves consequently spread apart, warp and twist. I aim to overcome this difficulty by constructing the column of a plurality of staves, all of which are of approximately the same relative taper, with one stave made of an inner and outer section substantially equal in length to the other staves. Through the staves I pass circumferentially of the column, a wire hoop or band, with the free ends of the wire emerging at the inner section of the sectional stave, where they are suitably joined and operate to bind the staves together. The outer section of the sectional stave covers and obscures the inner section and the connections between the ends of the several hoops. A column thus constructed presents on the outside no joints, except along the lines the several staves abut.

Reference is to be had to the accompanying drawings forming a part of this specification, in which similar characters of reference indicate corresponding parts in all the views.

Figure 1 is a side elevation of a column complete constructed in accordance with my invention; Fig. 2 is a plan of the same; Fig. 3 is a fragmentary elevational view of the column on an enlarged scale, with the outer section of the sectional stave removed; Fig. 4 is a section substantially on the line 4—4 of Fig. 3; and Fig. 5 is a fragmentary section similar to Fig. 4 on an enlarged scale.

In the construction of my improved column I employ a suitable number of staves all of which are of the same relative taper and preferably have engaging tongues and grooves formed on their abutting edges. All of the staves are of the same construction except one, which is made in two sections, an inner section 7 and an outer section 8, the inner section having the tongue and

groove corresponding to the tongue and groove of each of the other sections, and the outer section having longitudinal tongues 9 at opposite sides, preferably adjacent to its inner face, for engaging in counterpart grooves in the contiguous staves.

Each stave is provided at suitable intervals with a transverse aperture, preferably in line with its tongue and groove, which registers with like apertures in adjacent staves when the several staves of the column are placed together, and forms a passage for the reception of a band 10, preferably of wire, the free ends of the wire emerging in a slot 11 at the inner section of the sectional stave, and being reversely threaded, as best shown in Fig. 4. On the threaded ends of each wire is screwed a turnbuckle 12 having a transverse intermediate opening 13, through which it may be engaged in tightening the wire, this tightening action obviously operating to firmly bind the several staves of the column together. The turnbuckles all fall within the plane of the outer face of the inner section of the sectional stave in order that they will not interfere with the driving of the outer section of this stave into place, which driving obviously is in the direction of the small end of the column, should the column be of tapering form. After the column has been assembled it is in readiness to be turned to the required form, which can be performed without fear of loosening the staves.

I am aware that prior to my invention, stave columns have been in contemplation composed of a number of tapering staves, the tapering ends of which lie in the same direction; and one or more parallel staves, with a wire hoop passing through the several staves circumferentially of the column and binding the staves together, the ends of the wire where joined being covered by the outer section of one of the parallel staves, which outer section is made in two or more lengths. A column embodying this construction is disclosed in Letters Patent No. 840,639, granted to G. W. Loggie, January 8, 1907.

I, however, believe it to be broadly new to construct a column of a plurality of staves all of which are of approximately the same taper, with a band passing through the several staves circumferentially of the column and binding them together, one of the staves being made in two sections, on which line the ends of the bands are joined together and are covered by the outer section of the stave ex-

tending approximately the full length of the column. This construction not only embodies the desirable and efficient method of connecting the staves together, but permits 5 of all of the staves being made of the same relative taper, producing a column, when completed, having no transverse seams, which are objectionable in a finished column.

Having thus described my invention, I 10 claim as new and desire to secure by Letters Patent:

1. A column composed of a plurality of staves having abutting edges of the same relative taper, each stave having a transverse 15 aperture registering with a like aperture in the adjacent staves, a band passing through the aperture of the staves having its ends reversely threaded, and a turnbuckle engaging the threaded ends of the wire for drawing the 20 staves together.

2. A column composed of a plurality of staves of the same relative taper, with one of said staves consisting of an inner and outer section, the outer section being unbroken and 25 approximately equal in length to the other staves of the column, and a band passing through the several staves circumferentially of the column, with the free ends of the band joined together at the inner section of the 30 sectional stave.

3. A column composed of a plurality of staves of the same relative taper, said staves having engaging tongues and grooves on their abutting edges, and a band passing through the several staves circumferentially 35 of the column on a line intersecting the tongues and grooves, operating to bind the staves together.

4. A column comprising a plurality of staves, an inner stave section having a slot, a 40 wire band passing through the several staves, with its free ends reversely threaded and passing into said slot, a turnbuckle in said slot in threaded engagement with the threaded ends of the band, and an outer stave section 45 covering the inner stave section and the turnbuckle.

5. A column composed of a plurality of abutting staves, a band passing through the several staves circumferentially of the column, and a turnbuckle in threaded engagement with the free ends of the band for drawing the staves together.

In testimony whereof I have signed my name to this specification in the presence of 55 two subscribing witnesses.

CALVIN T. CUNNIUS.
